[57] CLAIM

The ornamental design for a child's boot, as shown and described.

DESCRIPTION

FIG. 1 is a left front perspective view of a child's boot showing my new design;
 FIG. 2 is a right rear perspective view thereof;
 FIG. 3 is a top plan view thereof;
 FIG. 4 is a bottom plan view thereof;
 FIG. 5 is a left side elevational view thereof;
 FIG. 6 is a cross-sectional view thereof as taken from line 6—6 of FIG. 7;
 FIG. 7 is a front elevational view thereof;
 FIG. 8 is a rear elevational view thereof; and
 FIG. 9 is a cross-sectional view thereof as taken from line 9—9 of FIG. 3.
 The above figures illustrate a right boot only, the left boot being an identical mirror image of said right boot.
